UNITED STATES PATENT OFFICE.

FINESS E. NEAL, OF ANDERSON, INDIANA, ASSIGNOR TO THE SEFTON MANUFACTURING COMPANY, OF ANDERSON, INDIANA, A CORPORATION OF INDIANA.

MACHINE FOR FACING CORRUGATED PAPER.

1,175,074.

Specification of Letters Patent. Patented Mar. 14, 1916.

Application filed October 9, 1911, Serial No. 653,703. Renewed May 8, 1912. Serial No. 696,002.

To all whom it may concern:

Be it known that I, FINESS E. NEAL, a citizen of the United States, residing at Anderson, in the county of Madison and State of Indiana, have invented certain new and useful Improvements in Machines for Facing Corrugated Paper; and I do declare the following to be a full, clear, and exact description of the invention, such as will enable others skilled in the art to which it appertains to make and use the same.

This invention relates to paper making, and more especially to machines for applying a flat strip to the face of a corrugated or cellular strip of paper; and the object of the same is to improve the construction of such a machine.

To this end the invention consists of the details hereinafter more fully described and 20 claimed and as shown in the drawings wherein—

Figure 1 is a side elevation of this machine complete; Fig. 2 is a horizontal section on the line 2—2 of Fig. 1; Fig. 3 is a front 25 elevation of the machine; Fig. 4 is an enlarged side elevation of the front end, and Fig. 5 a similar longitudinal section thereof; Fig. 6 is an enlarged cross section on the line 6—6 of Fig. 1; Fig. 7 is an enlarged 30 plan view of the paste box, and Figs. 8 and 9 are sections thereof on the lines 8—8 and 9—9 respectively.

It may be explained at the outset that single-faced corrugated paper is that composed of a cellular or corrugated sheet pasted upon or attached to a flat base sheet, the same being more or less flexible when bent in one direction and generally employed as packing for breakable articles 40 such as bottles and the like. Double-faced corrugated paper is that which comprises a corrugated sheet interposed between two flat sheets which are pasted or attached to its opposite sides, it is less flexible, and its 45 uses are varied. The object of the present invention is to produce a machine which will apply the second or facing strip to the upper or corrugated surface of a strip of single-faced corrugated paper already formed. 50 This is rather a delicate undertaking because the machine for applying the facing strip must be of such construction and operation that the corrugations or ribs are not crushed by pressure applied upon them nor

the base strip detached from the crowns of the corrugations of the corrugated strip as the whole passes through the machine. As the stock being handled is already to a degree cellular, it is impossible to heat it from the lower side, and yet heat must be applied that the second face or lining strip may be attached to the crowns of the corrugations by a paste composed of the silicate of soda which is usually employed for this purpose. Moreover, as any quick drying glue or one into which silicate of soda enters will harden on the face of the paste roll very quickly if left exposed to the air, said roll must be kept revolving in the glue or paste box whether the feed of the stock operated upon is maintained or checked, and my present invention contemplates provision for carrying out this feature.

In the accompanying drawings I have shown and in the following specification described in detail, a specific machine which embodies my invention in a preferred form, but it is to be understood that the specific disclosure is for the purpose of exemplification only and that the scope of the invention is to be found in the following claims in which I have endeavored to distinguish it from the prior art without, however, relinquishing or abandoning any portion thereof.

No claim is made herein to the production of single-faced corrugated paper which constitutes the "stock" upon which my machine operates.

Referring now to the accompanying drawings and more particularly to Fig. 1, the letter S designates a diagrammatic representation of the machine for turning out the single-faced corrugated paper or stock upon which my improved machine is to operate, said stock consisting of a base strip of flat paper and a corrugated strip superimposed thereupon and attached thereto by adhesive; and this stock is fed forward into the front end of my machine where I apply the upper or face strip of paper in a manner which will appear. Said machine is mounted upon a framework whose details of construction need not be amplified in this specification, and comprises at its front end means for applying and attaching the facing strip to the single-faced corrugated strip throughout its length and

means for pressing said parts gently together and drying them so that the product issues from the rear end of the machine in a condition ready for use. The front end 5 of said framework 1 carries a pair of brackets 2 each having in its horizontal arm a longitudinal groove 3 in which are a number of balls 4 as best seen in Figs. 3 and 4, and mounted upon said balls is the paste 10 pot or box 5 which has grooves 6 along its ends so that it is movably supported upon the balls in a manner which will be clear. Said paste box (best seen in Figs. 7, 8 and 9) has its front wall 7 vertical, its bottom 15 8 flat, and its rear wall 9 curved upward as shown in Fig. 9, and mounted on the upper edge thereof is a scraper 10 having a sharp or knife edge 11 projecting forward toward the paste roller 12 so as to remove therefrom the surplus paste. This scraper bar is slotted as seen at 13, and screws 14 engaging said slots pass into the upper edges of the ends of said box so as to permit the adjustment of said bar. The trunnions of the 20 25 paste roll are mounted in bearings 15 in the ends of the box, and one of them carries a gear wheel 16 and beyond that a sprocket wheel 17 connected by a chain 18 with a second sprocket wheel 19 on a stub shaft 20 mounted in the frame and revolved by the pulley 21 from any suitable source. The construction is such that, although the 30 35 paste box may be moved backward and forward upon the brackets, the chain connection between the driving and driven sprockets causes the paste roll to rotate constantly in the direction of the arrow in Fig. 4, so that paste is carried up on its ascending side, the surplus is scraped off by the 40 45 scraper. The constant revolution of the roll prevents the paste from hardening thereon.

Beneath the curved inner wall of the box is a cross bar 21' having an eye 22 to which 50 55 is loosely connected one end of a rod 23 whose other end is attached to a lever 25 (see Fig. 2), there being preferably a turn buckle 24 inserted within the length of this rod so that by manipulating the lever 25 60 65 the entire paste box and its roll can be set forward or backward for a purpose to appear below, but the rotation of the paste roll will not be interrupted. Notches 26 and 27 are provided in the framework 1, to be engaged by the lever 25 in its respective positions as seen in Fig. 2. When the lever is swung rearward the paste box and its roller will stand as seen in Figs. 4 and 5 and the single-faced strip S will be directed 70 75 between the brackets 2, around the curved rear wall 9 of the box 5, and beneath a presser roller 28 mounted in bearings 29 on the framework and the paste roller 5—it being my intention that the setting of the lever 25 and adjustment of the turn buckle

24 shall bring the paste box and its roller sufficiently near the presser roller 28 to permit the single faced paper to pass between said rollers without being crushed and yet to cause the ribs of the corrugated paper to be borne against the ascending side of the paste roller with just sufficient force to take the paste therefrom. Thus much of my machine constitutes what may be called the pasting mechanism.

The heating mechanism next to be described co-operates with the pasting mechanism in the application of the face strip to the single-faced corrugated paper, and together these two mechanisms make up the attaching means above referred to.

The numeral 30 designates a rotating cylinder or drum whose trunnions 31 are journaled in brackets 32 on the main frame, and one of them carries a gear 36 meshing with the gear 16 by which rotary motion is imparted to this drum whereas the other trunnion 33 is made hollow and is connected with a steam pipe 34 through a suitable valve 35. The numeral 37 designates a fixed ironing tube also carried by said brackets 32 and connected through a valve 35' with a steam pipe 34', this tube being located behind the drum 30 and above the presser roller 28 and spaced from the latter a sufficient distance to permit the material to pass between them.

The numeral 38 designates a tension roll disposed forward of and slightly above the drum 30. A strip of facing paper is fed from the roll 39 beneath the tension roll 38, thence over the drum 30 where it is heated on its lower side, thence between said drum and the tube 37 and beneath the latter where it is heated on its upper side, and by this tube 105 it is applied to the ridges of the single-faced corrugated paper at a point where the stock and the facing sheet pass between said tube and the presser roll 28 as best seen in Fig. 5. Thus the pasting means co-operates with the heating mechanism to attach the facing strip to the single-faced corrugated paper just at a time when said strip has been heated on both its under and upper sides and finally ironed out where it 110 passes beneath the tube, so that it is applied to the stock in a perfectly flat condition and while it is hot or heated on its under surface and adheres to the pasted corrugated strip quickly and permanently. It will be 115 observed that the drum 30 rotates and therefore draws the paper off the roll 39 and heats the same on its lower face as it passes over said drum, but the tube 37 is stationary and therefore the paper slips beneath it and is ironed while it is heated on its upper face and applied to the stock. The pressing or drying means next to be described coacts with the attaching means by drawing the products from the latter, pressing the facing 120 125 130

strip upon the ribs or ridges of the corrugations for a considerable period of time while the product is passing through the machine, and delivers the finished article at 5 the rear end thereof ready to be formed into rolls or cut into sheets or strips of any desired length.

Two pairs of shafts 40 are mounted in bearings 41 at the front and rear ends of the 10 framework respectively, and each shaft carries two sprocket wheels 42 just inside the sides of the framework, the wheels being connected by upper and lower sprocket chains 43 as shown. The chains at right 15 and left of the machine are connected by lagging bars 44 of any suitable type, and thereby are produced upper and lower endless belts whose width is equal to or greater than that of the stock and the finished product 20 and whose length is sufficient for the purposes of this machine. Around each belt I preferably dispose a canvas apron 45, and at the end of each belt this apron moves over a bar or roller 46 which draws it away 25 from the lagging where the slats or bars of the latter open in passing around the sprocket wheel and would therefore wear the apron. The parts are so disposed that the aprons come against the upper and lower 30 sheets of the product as it issues beneath the ironing tube 37, and hence said product is drawn from the attaching means and dried or pressed by the means just described before it is delivered at the rear end of the 35 entire machine. The rearmost pair of shafts 40 carry intermeshing gears 50 as best seen in Fig. 6, one of which meshes with a power gear 51 connected by a clutch mechanism 52 with a pulley 53 receiving its power from 40 any suitable source not shown; and said lever 25 is connected by a rod 54 through a bell crank lever or other mechanism 55 with this clutch 52 so that when the lever is moved the clutch is opened or closed. The 45 power is applied to the pulley 53 to rotate the power gear 51 at such speed that the drying mechanism will draw the product only as rapidly as it can be successfully treated by the attaching mechanism; but 50 when for any reason the lever 25 is manipulated to open the clutch 52 and check the movements of said aprons and therefore interrupt the passage of the stock through the drying mechanism, the rod 23 moves the 55 pasting mechanism bodily forward as seen in dotted lines in Fig. 1 so that the gear 16 is thrown out of mesh with the gear 36, the rotation of the drum 30 ceases and the feed of the facing paper from the roll 39 is 60 interrupted for precisely the same length of time as the movements of the aprons is interrupted, whereas the rotation of the paste roller within the paste box continues. This I consider an extremely important feature 65 of my invention because as stated above

the character of the paste employed in these machines is such that it very quickly gums and hardens upon the surface of the roller if the latter remains stationary within the paste box or pot. Interruptions of the 70 character suggested are of frequent occurrence, as when the attendant adjusts some part of the machine, or the roll of stock S becomes exhausted and must be replaced by 75 a new one; and it is quite within the possibilities of this invention that the same attendant may have charge of the mechanism for producing the single-faced paper, which mechanism must of course be operated at a corresponding speed so that the stock produced thereby can be supplied as rapidly as the facing strip is applied by this machine. The parts of the latter may be of any desired sizes, shapes, proportions and materials, and such changes in details of construction can be adopted as come within the spirit 85 of my invention.

The operation of the whole will be familiar to those expert in this art from the description above given.

What is claimed as new is:

1. In a machine of the class described, the pasting mechanism including a power-driven paste roll rotating constantly in the paste, feed mechanism including a rotary drum, gears on the trunnions of said roll and drum whereby the drum is driven from the paste roll, and means for moving the paste roll so that its gear will disengage that on said drum but the rotation of the roll will be un- 100 interrupted.

2. In a machine of the class described, the pasting mechanism including a pressure roller and means co-operating therewith to compress material passing between the same, a paste box movable toward and from said pressure roller, a paste roll therein having a sprocket and a gear on its trunnion, and a chain connecting the sprocket with a stationary driving sprocket; combined with feed mechanism for a lining strip including a rotary feeding drum and a gear on its trunnion adapted to mesh with that on said roll, and a lever connected with said box for moving the pasting mechanism bodily so that the gear on its roll will engage and disengage that on said drum but the sprocket connection with the stationary sprocket will be uninterrupted.

3. In a machine of the class described, the combination with means for attaching the paper strip to the corrugated paper, the same including a pasting mechanism, a feeding mechanism, and driving connections between the two; of means for drying and conveying the product produced by the attaching means, power means for driving the drying and conveying means, a clutch between the last said means and said power means and controlling mechanism connected to said 120 125 130 135 140 145 150 155 160 165 170 175 180

clutch and driving connections for simultaneously opening the first and rendering inoperative the second.

4. In a machine of the class described, the combination with means for attaching a facing strip to a strip of corrugated paper, the same including a rotary pasting roll and a movable box in which it is mounted, a rotary feeding drum, gears on said drum and roll adapted to intermesh; of means for drying and conveying the product produced by said attaching means, the same including two co-acting belts having parallel runs adapted to receive the material from the attaching means between them, a source of power, driving connections from said source of power to said belts, a clutch in said connections for connecting and disconnecting said source of power to and from the belts and controlling mechanism adapted to simultaneously open said clutch and move said box to disengage said gears.

5. In a machine of the class described, the combination with a paste box movably mounted on a support, a constantly driven roll mounted in said box and dipping into the paste, a presser roll with which said paste roll co-acts in one position of the box, and a feed roll rotating in fixed relation to said presser roll; of gears on the trunnions of the paste roll and feed roll intermeshing when the former stands adjacent the presser roll, and means for moving said box to throw the gears out of mesh.

35 6. In a machine of the class described, the combination with a presser roll, a paste box, a power-driven paste roll rotating constantly in the paste, feed mechanism for a strip to be pasted rotating in fixed relation to said presser roll, and severable connections between the paste roll and feed mechanism; of the drying mechanism, a source of power for driving the same, a clutch between the drying mechanism and its source of power, and controlling mechanism for simultaneously opening said clutch and severing said connections.

7. In a machine of the class described, the combination with a presser roll, and a pasting mechanism including a box and a paste roll means for rotating said roll constantly in said box and said box and roll adapted to be moved toward or from said presser roll; of two coacting belts having parallel runs adapted to receive the material from the presser roll between them, connections between said belts and a source of power, a clutch in said connections for connecting and disconnecting the source of power from said belts, a lever, and rods connecting it with the clutch and the box whereby the position of these elements may be simultaneously controlled.

8. In a machine of the class described, a paste box having a curved rear wall, set

screws in its upper edge, and a scraper bar adjustably mounted on said set screws with its knife edge projecting over the box; combined with a paste roll whose trunnions are journaled in the ends of the box, means for rotating the roll constantly, a presser roll, and means for moving the box and roll toward and from the presser roll.

9. In a machine of the class described, the combination with a relatively fixed presser roll, and a pasting mechanism movable toward and from said roll and including a constantly driven paste roll and a gear wheel; of a heating mechanism comprising a rotary heating drum having a gear wheel adapted to mesh with that on the pasting mechanism when the latter stands adjacent the presser roll, a fixed ironing tube contiguous to the drum but spaced from and coacting with the presser roll, and means for heating said drum and tube.

10. In a machine of the class described, the combination with a framework, a pair of brackets thereon, a presser roller journaled therein, an ironing means co-acting with said presser roller, means for feeding a strip of corrugated paper and a facing strip between said roller and ironing means, of a second pair of brackets mounted on said framework, a pasting mechanism, including a box and a paste roll mounted in said box and adapted to co-act with said presser roller to apply paste to corrugated paper on the latter, means for rotating said paste roll and means for moving the pasting mechanism bodily along its brackets toward and from said presser roller.

11. In a machine of the class described, the combination with a pair of spaced brackets between which the stock is fed; of a paste box movably mounted on said brackets and having a curved rear wall forming a guide around which the stock passes, a paste roll rotating constantly in said box, means for constantly rotating the same, a relatively fixed presser roll between which and the paste roll the stock passes, a cross bar on said box below its curved wall, an eye on said bar, a controlling lever, and a rod connecting the same with said eye.

12. In a machine for corrugating paper, a presser roller and means co-operating therewith to attach a facing strip to a corrugated strip, means for receiving the corrugated board so formed and drawing it between said presser roller and co-operating means, a power means for driving said receiving and drawing means, a clutch between said power means and receiving and drawing means, a clutch shifter, a paste roll, a paste box in which said roll dips and which is adapted to be reciprocated by means common thereto and to said clutch shifter whereby said paste roll is continuously driven irrespective of the position of the clutch.

13. In a machine for facing corrugated paper, a presser roll and means coöperating therewith for attaching a facing paper strip to a corrugated strip, between which the 5 corrugated paper and the facing strip is fed, means for receiving and drawing the corrugated board from said pressing members, means for actuating the same including a clutch for disconnecting the receiving means from the source of power, a paste roll, a 10 paste box in which said roll dips, means independent of said clutch for driving the paste roll, a feeding roll for the strip of facing paper, means for driving the same from the paste roll, means for simultaneously 15 operating said clutch and disconnecting the paste roll from the feed roll.

14. In a machine for facing corrugated paper, pressing means, a paste roll movable 20 into and out of operative relation thereto, a roll for feeding the facing strip to said pressing means, means for driving the feeding roll, means for driving the paste roll in and out of operative relation with the pressing means, means for simultaneously moving the paste roll out of operative relation 25 to the pressing means and disconnecting the paste roll from the feed roll.

15. In a machine for facing corrugated 30 paper, pressing means, a paste roll movable into and out of operative relation to the pressing means, a roll for feeding a facing strip to the pressing means, means for driving the paste roll in and out of operative relation with the pressing means, connecting means for driving the feed roll from the 35 paste roll, and means for simultaneously moving the paste roll out of operative relation to said pressing means and disconnecting the paste roll from the feed roll.

16. In a machine for facing corrugated board, a pressing means, a paste roll movable into and out of operative relation to the pressing means and carrying a gear wheel 45 on its shaft, a roll for feeding the facing strip to the pressing means also having a gear upon its shaft adapted to be engaged by the gear upon the shaft of the paste roll, means for driving the paste roll into 50 and out of operative relation with the pressing means, means for moving the paste roll and its gear into and out of operative relation with the pressing means and the gear on the feeding roll respectively.

55 17. In a machine for facing corrugated paper, a presser roller, a non-rotating ironing means directly coöperating therewith to attach a facing strip to a corrugated strip of paper and means for receiving and drawing the faced board from between the presser roller and ironing means.

18. In a machine for facing corrugated 60 paper, a presser roller, a non-rotating ironing means coöperating therewith to apply a facing strip to a corrugated strip, means

for feeding the facing strip to said ironing means between it and the presser roller and means for receiving and withdrawing the completed board from between the ironing means and the presser roller.

70 19. In a machine for facing corrugated paper, a presser roller, a non-rotating ironing means coöperating therewith to apply a facing strip to a strip of corrugated paper, means for feeding a facing strip to said ironing means between it and the presser roller, means for heating said ironing means and means for receiving and withdrawing the completed board from between the ironing means and the presser roller.

75 20. In a machine for facing corrugated paper, a presser roller, a non-rotating ironing means coöperating therewith, for applying the facing strip to the corrugated paper strip, means for heating said ironing means, means for feeding a facing strip to said ironing means between it and said presser roller and means for receiving and withdrawing the completed board from between the ironing means and the presser 80 roller.

85 21. In a machine for facing corrugated paper, a presser roller and an ironing means, means for drawing the corrugated board therethrough and clutch controlled means for driving the latter, a paste roll movable into and out of operative relation to the pressure means, a paste box into which said roll dips, means independent of the clutch controlled means for continuously 90 driving the paste roll in every position thereof.

95 22. In a machine for facing corrugated paper, a presser roller and an ironing means, means for drawing corrugated board therethrough and clutch controlled means for driving the latter, a paste roll movable into and out of operative relation to the pressure means, a paste box into which said roll dips, means independent of the clutch controlled means for continuously driving the paste roll in every position thereof, a roll 100 for feeding a facing strip to the pressure means and connections between the same and the paste roll for operating the former 110 when the paste roll is in operative position.

115 23. In a machine for facing corrugated paper, a pressure means, a paste roll, a paste box into which the latter dips, having a curved face adjacent the pressure means 120 serving as a guide for the strip of corrugated paper to be treated.

125 24. In a device of the class described, pressure means, rotary means for feeding a lining strip thereto, means for feeding a corrugated strip to said pressure means, a paste tank, a paste roll journaled therein and dipping in the paste, means for moving the tank to bring the paste roll into and out of the path of the corrugated strip, con- 130

stantly rotating means connected to the paste roll to drive the same irrespective of its position and gears on the paste roll and lining strip feeding means respectively whereby when the paste roll is in position to engage the corrugated strip said gears are in engagement and the paste roll drives the said feeding means and when the paste roll is out of position to engage the corrugated strip said gears are out of engagement.

25. In a machine for facing corrugated paper, a presser roller and ironing means coöperating therewith between which the facing and corrugated strips are fed, power means for driving one of said members, a clutch between said driving means and member, a paste box, a paste roll mounted in said box, said box being movable toward 20 and from said presser member, a stationary driving shaft, independent of said clutch, and connections from said stationary shaft for driving the paste roll irrespective of its position.
26. In a machine of the class described, a pair of pressure rollers, lagging arranged to receive the finished product from the

pressure rollers, driving means for the lagging, a clutch between the driving means and lagging, a paste box movable toward 30 and from one of the pressure rollers, a paste roll in said box adapted to be brought into and out of the path of one of the sheets to be united, means for moving the paste box, a manually operated means for moving the 35 paste box and for shifting the clutch.

27. A machine of the class described, a pair of pressure rollers, lagging arranged to receive the finished product from the 40 pressure rollers, driving means for the lagging, a clutch between the driving means and the lagging, a paste box, a paste roll adapted to be brought into and out of the path of one of the sheets to be united, manually operated means for moving the 45 paste roll and for shifting the clutch.

In testimony whereof I have hereunto set my hand in presence of two subscribing witnesses.

FINESS E. NEAL.
